SAFETY SEAT

Vernon B. Stewart, Dearborn, Mich.

Application June 4, 1937, Serial No. 146,508

2 Claims. (Cl. 155—5)

This invention relates to improvements in resilient chairs, and particularly concerns that class employed in aeroplanes.

One of the principal objects of my invention is to provide a chair adapted for use in aeroplanes having means incorporated therewith to effect a maximum amount of safety in case of accidents.

Another object of my invention is to provide a chair having means which may be adjusted to 10 the needs and requirements of each individual passenger, thereby affording a maximum amount of comfort.

Other objects and advantages will be apparent from the following description, appended claims, 15 and annexed drawings.

An illustrative form of practicing my invention is set forth in the accompanying drawings wherein like characters designate like parts throughout the several views.

In these drawings:

Fig. 1 is a front view of my invention.

Fig. 2 is a sectional view taken on a line 2—2 of Fig. 1.

Fig. 3 is a fragmentary enlarged sectional view 25 taken on the line 3—3 of Fig. 1.

Fig. 4 is a plan view of the blank from which the base or bottom of the seat is formed.

Fig. 5 is a detail sectional view illustrating the mechanism for adjusting the back.

Fig. 6 is a detail sectional view of the resilient 30 back member.

According to the present invention, my chair comprises a substantial and rigid base member or bottom 10 formed with front and rear legs 11 and 12, the legs being secured to the floor within 35 a cabin of an aeroplane as at 13. The sides of the chair, between the legs, base, and floor of the cabin, are enclosed by side panels 9, connected to said legs and base. A seat 14 is adapted to be positioned upon the base 10 and is composed of flexible material, preferably sponge rubber, the walls of which are inflated by air induced therein through a suitable valve 15.

Arm frames 16, having ends secured to the legs 45 12, extend upwardly to form curved arm rests 17, the curved ends of which are secured to the base 10, as at 18. The arm frames are provided with soft resilient material 19, preferably sponged rubber, as illustrated in Fig. 2 of the drawings.

An adjustable back 20 comprises a pair of 50 cushions 21 and 22. The cushions being constructed of soft pliable material, such as sponge rubber or the like, the walls of the cushion 22 adapted to be inflated by air, induced therein through a suitable valve 23. The cushions 21

and 22 are positioned adjacent an intermediate protective member 24 adapted to fit over a pair of parallel spaced spring steel plates 25, the lower portions of said plates gradually increasing in thickness in a downward direction. The upper sections are of a high degree of flexibility and are disconnected to receive therebetween, for the purposes hereinafter described, additional spring plates 26 which serve to reinforce the structure. The lower ends of the plates are connected together and have formed thereon a plurality of depending ears 27 projecting through and working in apertures 28 formed in the base 10. The ears 27 are provided with segmental-shaped slots 29 having radially disposed faces for the reception 15 of a similarly shaped locking bar 31 provided with locking faces 32 and 33. The ends of said bar extend beyond the edges of said plates and are journaled in openings formed in the side panels 9 for pivotally supporting the back, as illustrated 20 in Figures 1 and 3. The faces 32 and 33 of the bar are adapted to engage the under face of the base, between the depending lugs, to limit the forward or backward movement of said back. A spring 34, secured to one of the legs 12, engages 25 a depending lip 35 formed at one end of the bar 31 and urges the back rearwardly in relation to the seat. The lugs are provided with ratchet teeth 36 formed on their inner faces for engagement with teeth-engaging sections of a resilient 30 pawl member 37 secured to the under side of the base 10, as shown in Fig. 3.

Interposed between the pawl member 37 and the base 10 is a pawl operating bar 38 for disengaging the pawl member from said ratchet 35 teeth. The bar, which is relatively flat in cross section, is journaled in the side panels 9 and operated by means of the handle 39.

A casing 40 of suitable material covers the cushions 21 and 22, holds them together and is 40 secured to the intermediate protective member 24.

It will be apparent from the foregoing that the back 20 may be adjusted to any desired inclination to suit the needs of each individual passenger. The preferred manner of adjusting the back 45 is to release the pawl member 37 from engagement with the ratchet teeth 36 on the lugs 27, move the back 20 rearwardly until the face 32 of the bar 27 engages the under face of the base; the pawl member is then released to permit engagement with the teeth. At this point in the adjusting operation, the passenger is seated within the chair and reclines against the back, the back is then adjusted to effect the most comfortable 50 position for the passenger. Should the back, due 55

to the weight of the passenger, be too flexible, the cushions 21 and 22 are removed and a suitable number of additional spring plates 26 inserted between the plates 25. Should a reverse condition prevail, for example, the back being too stiff, plates 26 may be removed. The spring 34 while normally urging the back rearwardly also serves to hold the ratchet teeth 36 in engagement with the pawl member 37 to secure the back in the desired position. The air inflated cushions 14 and 22 readily adjust themselves to the posture of each individual passenger.

In those cases, involving an accident, where a passenger is catapulted from another chair located in the rear against the back 20, said back will move forward until the face 33 on the bar 31 abuts the lower face of the base 10. This action coupled with the resilient nature of the cushion 20 will greatly lessen and absorb the shock, thus minimizing injuries.

It is to be distinctly understood that many changes and modifications of the form herein described and illustrated may be resorted to without departing from the spirit of the invention or scope of the appended claims.

Having described my invention, what I claim is:

1. A resilient chair, comprising, a seat, a detachable back having a plurality of spaced resilient plates connected at one end and terminating in hinge members, a locking device car-

ried by said seat and pivoting said back to said seat, said device coacting with said members to limit the movement of said back relative to said seat, said plates resiliently yieldable to absorb impact transmitted to said back to preclude deformation of said locking device when actuation of the latter is arrested by movement of said back, and auxiliary plates interposed between said first mentioned plates for governing the yieldability of said first mentioned plates.

2. A resilient chair, comprising, a seat, a back detachably connected to said seat and having a plurality of spaced resilient plates connected together at one end and terminating in hinge members, a bar carried by said seat and coacting with said members to limit the movement of said back relative to said seat, said bar constituting the pivot connection between said back and said seat, detachable plates interposed between said first mentioned plates for regulating the yieldability of the latter, and a latch engaging said hinge members and coacting therewith to maintain said back against movement in one direction and permit movement in another direction, said plates resiliently yieldable to absorb impact transmitted to said back to preclude deformation of said members and said bar when movement of said back in said last mentioned direction is arrested by said bar.

VERNON B. STEWART. 30
